Application October 22, 1952, Serial No. 316,212

11 Claims. (Cl. 237—67)

The invention relates to a new or improved, steam driven pump mechanism, particularly for use in connection with a steam heater system for returning condensate from heater units to a steam generator. In domestic and other steam heating systems it is desirable to employ a closed fluid circuit in order to conserve water and heat; and, in installations such that the condensate cannot be returned to the generator by gravity, a pump of some kind has to be used. Steam and electrically driven pump mechanisms are available for the indicated purpose but usually at relatively high cost. The electrically driven pumps require a power source extraneous to that of the heater system. An object of the present invention is to provide a simple and inexpensive automatically and efficiently operating, condensate pump mechanism which does not require an extraneous power source.

Other objects will become apparent from the following description of a preferred form shown in the drawings wherein:

Fig. 1 is a schematic view showing a closed fluid circuit type steam heater system and one manner of connection of the subject pump mechanism or unit therein (unit size exaggerated with respect to other elements of the system).

Fig. 2 is a plan view of the pump unit in three quarter scale (covers removed).

Fig. 3 is a sectional view taken along the line 3—3 on Fig. 2.

In Fig. 1, A represents steam generator or boiler having a steam line A' connected to supply a plurality of heaters or radiators, one indicated at B, having a condensate return line C. Line C is connected to the subject pumping unit D, the main body 1 of which is an unsealed, i. e. freely air-vented tank. A steam line E connected with the generator supplies a steam turbine assembly F of unit D through a valve mechanism G which is operated cyclically in response to changes in liquid depth or quantity in the tank, as by a float H. The float is connected to the valve by a snap-action or toggle mechanism J which effects rapid valve movement to "on" and "off" positions at maximum and minimum liquid levels respectively. The condensate pump (impeller K) connected to the turbine receives condensate from a filter chamber R, has a pump chamber L provided with an outlet duct for condensate, a helical-chamber-providing portion M of which duct is in heat exchange relationship to a turbine exhaust steam condensing space or chamber N, which latter is in open liquid flow enabling communication at O with the main liquid content space of the tank. The pump outlet duct portion M is conventionally connected, as by line P, to the steam generator A.

If the heater B of Fig. 1 is made according to Patent No. 2,692,759 granted October 26, 1954, to Marcus O. Swenson and Paul F. Swenson, then the condensate in line C will have its maximum temperature limited, by an

2

emergency control shown in that application, so as to be well below the average boiling point of water (actually to around 170 degrees F.) whereby the temperature of all the water in tank 1 is adequately low to enable its use as a condensing fluid medium for the exhaust steam of turbine F. If no provision is made in heater B to limit maximum heating medium return temperature then it is assumed that some other temperature limiting means would be used. Normally the tank 1 is located far enough from the heaters to insure an adequately low liquid temperature in the tank for turbine exhaust steam condensing purposes. The subject pump, for reasons which will become evident, is however able to return the condensate back to the boiler even though the condensate, as received from the heater units, is at the boiling point, i. e. too high a temperature to insure condensation of turbine exhaust steam wholly within the unit D.

Referring to Figs. 2 and 3, the tank body 1, as shown, is made as a simple rectangular sheet metal vessel flanged inwardly as at 2 around its open top for support of the turbine and pump assembly F, L etc., and suitable cover sections 3 and 4 (Fig. 3 only). Cover section 3 closes only the tank portion in which the float H and connected snap action steam valve mechanisms J and G are disposed. Section 4 forms a top wall for a turbine impeller housing having a central cup-like portion depending into the tank and containing an impeller wheel 6 co-operating with steam nozzle 7 in the manner shown at the upper right in Fig. 2. The turbine, as shown, is generally the same as one more fully described in the Swenson et al. application.

Turbine housing member 5, as shown, is formed from sheet metal as a shallow, generally rectangular, pan with a top rim or flange 8 extending over the tank side walls and one end wall as best shown in Fig. 2. Portion 8' of the flange supports a fitting 9 which forms the body of the steam valve G. Fitting 9 supports the float H. Flange portion 8' has an opening 10 into which the condensate line C from the heater or heaters extends loosely. The opposite side 8" of the flange 8 carries a fitting 11 to which pump outlet line P is connected.

The bottom wall of turbine housing member 5, at a self-aligning bearing assembly 12, described later, carries the turbine output shaft 14, and the lower end of the shaft is radially supported by a similar self-aligning bearing assembly 15 mounted on a cylindrical stiff upright tube 16 depending from the turbine housing member 5 and detachably secured to it as by screws. Tube 16 is the principal part of pump chamber L around and in radially spaced relation to the shaft. The bearing assemblies and their supports act as fluid blocking or sealing closures for the upper and lower ends of the tube 16 thus defining therewith the generally closed pump chamber L. The lower shaft support and closure assembly 15, see Fig. 3, includes a generally rectangular filter supporting stamping 18 the top wall of which slopes downwardly in all directions from its region of attachment to the tube 16. A laminated filter body 20, preferably largely of spun glass, is supported by a one piece sheet metal frame 21 having substantially identical side-forming elements of channel shaped cross section whose flanges embrace the filter body margins and downwardly stepped continuous flange portions of stamping 18. The filtered-water-chamber R, which is self-emptying of air or gas bubbles, is thus maintained for supplying the pump inlet which, as will be described, is constituted by a hollow lower end portion of shaft 14. Two relatively adjacent side-forming elements of the frame 21 (e. g. at one corner of the frame) are detachably secured together by a suitable clip not shown.

The self aligning and fluid sealing features of the bear-

ing assemblies 12 and 15 are obtained in part by provision of carbon bushings 22 and 25 of identical form, each with a polished bore nicely fitting a respective portion of pump shaft 14 and each having a generally spherical head 24 received in mating central portions of the respective members 5 and 18. The spherical heads of the bushings are held in tight sealing contact with their mating supporting surfaces by retaining spring metal discs 26 and 27 engaging respective spherical heads. Snap rings 22' and 22" around the shaft 14 abut relatively adjacent ends of the bushing 22 to hold the shaft vertically in working position. The shaft 14 is preferably stainless steel and, except for the snap-ring-receiving grooves in the shaft, the latter is of uniform diameter in and below the hub 6' of the turbine impeller.

The pump rotor or impeller K is a smooth circular metal disc 28 having a hub portion 28' for attachment of the disc to the shaft. The disc preferably has a single diametral bore which forms two substantially radial passages 29 communicating at their inner ends with an axial bore 30 in the bottom end of the shaft 14, which end of the shaft is always immersed in liquid contained in space R between the lower pump chamber closure and the filter 20.

It is important that the steam valve control mechanism G, H, J be so designed that, at minimum liquid level of condensate in the tank, the impeller of the pump will be below that level. Assuming such design and ample flow capacity of the filter, the mechanism, partly due to maintenance of at least some pump-supply water head, insures boiler water replenishment whether or not (as due to too high temperature condensate return from the heaters) all the turbine exhaust steam is condensed in the chamber N.

The smooth axial faces of the impeller disc 28 and its smooth circular periphery are spaced considerable distances from the nearest surrounding walls defining the pump chamber L, so that fluid drawn into the shaft bore 30 and ejected centrifugally by the radial passages 29 is free to flow in any required direction away from the impeller. The outlet to the pump chamber (fitting 32, for helical outlet duct described later) is preferably near the top of the pump chamber in order that no substantial volumes of air or vapor which may be entrained in the water as by operation of the pump at very high speed on high temperature condensate, will be trapped in the pump chamber.

The exhaust steam from the turbine chamber passes through exhaust ports 34 in housing member 5 into annular condensing chamber or space N formed around and constituted in part by the pump chamber wall 16 in co-operation with a relatively surrounding sheet metal sleeve 36. The sleeve 36 is suitably sealed at its upper end around the external periphery of turbine housing member 5 by which the sleeve is supported in the tank. The lower end of the sleeve 36 is open, as by being spaced uniformly above the bottom of the tank, but said end of the sleeve is continually immersed in water (lower edge of sleeve below minimum water level permitted by cyclical action of the float controlled mechanism as will be apparent), in order to maintain a water seal for the chamber.

Normally to insure condensation of all the turbine exhaust steam in annular space N the outlet fitting 32 of the pump chamber has connected therewith the single helical coil of metal tubing M leading to output fitting 11, thus forming a condensing-medium-chamber having a relatively large effective heat exchange surface within the chamber or space N and concentric therewith for increasing surface exposure to turbine exhaust steam as its volume increases or the space for it is enlarged by lowering of the general water level in the tank. The coil M, moreover, has adequate condensing surface area to insure that the exhaust steam will remain trapped in chamber N under negligible pressure so that turbine efficiency does not tend to be reduced by increase of exhaust steam pressure and so that no portion of the exhaust steam will be

ejected into the vented general tank space around the sleeve 36 and result in loss of water from the heater system.

The effective condensing-chamber-defining surfaces of 5 the tube 16, of the surrounding sleeve 36 and of the pump outlet tube M all increase as the height of the steam-trapping water column maintained within the available condensing chamber space N diminishes.

The steam valve chamber provided by fitting 9 is normally closed by a poppet type plug 40 to block passage of steam to turbine nozzle 7. A stem portion 41 of the plug slides in a guide bore in the fitting 9, below which the stem has a double flange or spool formation 42. A channel shaped bracket 43 is secured rigidly to the lower end of 15 fitting 9 and the bracket is designed to afford a free pivotal support at 44' for a steam-valve-operating yoke 44, made as a stiff metal plate, and, further, to form or provide another differently located free pivot, as at 45', for a snap action toggle yoke member 45, shown as of U-shape as 20 viewed in Fig. 2. Yoke plate 44 loosely straddles the spool formation 42 of the valve stem.

Yoke 45 is directly attached to a stiff, float-supporting arm 46; and a pair of tension coil springs 47 are connected for over-centre toggle action between the yoke 45 and 25 valve-actuating plate 44. Vertically spaced apart lugs 48 on yoke 45, positioned for abutment with a side wing 44" (Fig. 2) of the plate 44, tend to insure opening and closing movement of the steam valve (as the float approaches its high and low water-level-determined positions, respectively) in case of deterioration of the springs 47 or in 30 case the valve or its actuating plate 44 cannot, from any cause, be moved freely by toggle spring action alone.

The springs 47, for adjustment of their effective forces, and in order to enable them to be made inexpensively and 35 of long useful life, are secured at their ends by machine screws 49 having rounded under-head surfaces seated in conical depressions in the screw-supporting parts and with their threaded shanks engaging the associated spring end coils. The coils effectively lock the screws, by well known 40 "spring clutch" action against turning in the necessary direction to relieve the adjusted tension of the springs, and adequately restrain the screws from turning in the opposite direction solely by friction.

Referring further to the operation of the mechanism described above, the steam valve G remains closed until 45 the accumulation of condensate in the tank 1 causes lifting of float H to about its full-line-illustrated position, Fig. 3, whereupon the turbine operates the condensate pump K to supply the generator A until depletion of condensate in the tank allows the float to move to approximately its broken-line-illustrated position at which the steam is quickly and fully turned off, completing the operating cycle. The steam pressure and the force of the snap action mechanism springs hold the valve G fully closed. Due to the illustrated turbine design, the light load imposed on the turbine by the relatively small circular pump impeller K in its non-confining chamber and to the nearly-friction-free, self-aligning, carbon bearings of the shaft 14, the turbine (supplied with steam at around 6 to 10 p. s. i. as a typical pressure for domestic heating) turns 55 its output shaft assembly at between 5,000 and 7,000 R. P. M. At 10 p. s. i. steam pressure the pump has been found to deliver about 400 pounds of water per hour. The turbine exhaust steam is fully condensed without breathing loss in chamber N at a rate such as will allow 60 efficient turbine action if the temperature of condensate, as returned to the unit D, is below 180 degrees F.

In case, due to faulty (e. g. dirt-restrained) operation of the snap action valve mechanism J, the steam valve is not fully opened and the turbine is therefore not 65 supplied with steam at a high enough rate to effect high speed rotation of its impeller, accumulation of steam in the condensing chamber space N, by depressing the water column in that chamber, tends to raise the level of water in the float-containing or main part of the tank, thus aiding the toggle mechanism in fully and quickly opening

the steam valve. Since the heat of the steam used to operate the turbine is mainly returned to the steam generator with the condensate output of the pump the operating expense of the described mechanism is negligible. Even friction "loss" is conserved as heat.

I claim:

1. A condensate pumping mechanism for a steam heater system or the like, comprising a tank, a low pressure steam turbine associated with the tank and having an upright output shaft, a steam supply valve for the turbine, tank-liquid-level or quantity controlled means to move the valve to "on" and "off" positions, a centrifugal pump having an impeller coaxial with said shaft and connected thereto for operation by the turbine, the pump having an inlet continually immersed in liquid contained by the tank and having an outlet duct, means in the tank forming a condensing chamber for the turbine, means connecting the outlet of the turbine with said condensing chamber at a predetermined level, said chamber having an inlet in communication with the tank and opening into the chamber at a lower level, a portion of the pump outlet duct being located within the chamber between said levels for direct exposure to exhaust steam therein when the condensate is at a predetermined level, and the outlet duct of the tank being uncommunicated with the interior of the chamber and tank.

2. In combination, an open or vented storage tank for condensate of a steam heater system, steam admission valve means operated to "on" and "off" positions by low and high liquid level in the tank, a steam turbine supplied through said valve means, the turbine having a rotary output shaft extending downwardly into the tank, a condensate pump connected with the shaft and having a condensate inlet continually immersed in liquid in the tank, wall means forming into upright chambers, one of the chambers surrounding the pump and receiving its liquid output and the other chamber forming a receptacle for turbine exhaust steam, said receptacle having an opening at its lower end in position for continual immersion in liquid contained by the tank, and the wall means forming at least one of the chambers having a steam-condensing wall surface portion, exposed, during operation of the turbine, to exhaust steam contained in said other chamber, in a manner such that as the depth of condensate in said other chamber decreases, the condensing surface area exposed to exhaust steam increases.

3. In combination, an open or vented storage tank for condensate of a steam heater system, steam admission valve means operated to "on" and "off" positions by low and high liquid level or quantity in the tank, a steam turbine supplied through said valve means, the turbine having a rotary output shaft extending downwardly into the tank, a condensate pump connected with the shaft and having a condensate inlet continually immersed in liquid in the tank, wall means forming three chambers, each in surrounding relationship to the shaft axis, and including a first chamber surrounding the pump and receiving its liquid output, a second chamber forming a receptacle for turbine exhaust steam, which receptacle receives such steam at its top end and is open near the bottom of the tank for continual immersion in condensate contained by the tank, and a third chamber forming part of an outlet duct for liquid received by the first chamber to conduct such liquid from the tank, and the third chamber having steam condensing wall surface portions exposed, during operation of the turbine, to exhaust steam contained in the second chamber.

4. In combination, an open or vented tank adapted to store condensate liquid as from a steam heater en route to a steam generator, a steam driven turbine having an output shaft supported for rotation on an upright axis extending toward the bottom of the tank and connected to a centrifugal liquid impeller having an inlet passage in position to be continually immersed in liquid contained by the tank, two wall members providing an upright

annular condensing chamber connected at its upper end to the turbine for reception of turbine exhaust steam, the chamber at or near its lower end being open for discharge of turbine exhaust steam condensate into the tank, one of the wall members surrounding the other, the inner one of the wall members defining said annular chamber forming an imperforate side wall of a pump chamber around the impeller, and means connected to provide a pump-chamber-discharge duct located in said annular chamber and having a steam-condensing surface portion adapted to be exposed directly to exhaust steam in said chamber in amounts increasing with the increase in volume of uncondensed steam.

5. The arrangement according to claim 4, wherein said pump-discharge-duct-forming means is a metal tube connected to an upper end portion of the pump chamber and coiled into a helix in the condensing chamber.

6. In combination, an open or vented storage tank for condensate of a steam heater system, steam admission valve means operated to "on" and "off" positions by low and high liquid level or quantity in the tank, a steam turbine supplied through said valve means, the turbine having a rotary output shaft extending downwardly into the tank, the shaft having a hollow bottom terminal portion, a circular disc coaxial with, and rotatable with, the shaft and having generally radial passages communicating with the hollow portion to provide a centrifugal pump element for the condensate, wall means forming three chambers, each in surrounding relationship to the shaft axis, and including a first chamber containing said pump element, a second chamber forming a receptacle for turbine exhaust steam, which receptacle, at or near its lower end, is in open communication with condensate in the tank, and a third chamber disposed within the second chamber and forming a helical outlet duct for the pump-containing chamber, and wall surfaces defining the third chamber being exposed to exhaust steam during operation of the turbine.

7. In or for a heater system, condensate transfer mechanism comprising a steam-turbine-driven pump including an upright shaft, a tubular approximately cylindrical housing surrounding the shaft with its circumferential wall in radially spaced relation therefrom, closures for the two ends of the housing, fluid sealing, self-aligning journal bearings for the shaft in respective closures, a steam turbine assembly above the upper closure connected to drive the shaft, a circular pump-forming disc on and concentric with the shaft and located between the closures, said shaft having a downwardly extending axial liquid inlet passage which has its inlet end in communication with the space outside of the housing, said disc having generally radial passages formed therein and communicating with said inlet passage, the perimeter and axial faces of the disc being spaced respectively from the housing wall and said closures sufficient distances so that the liquid ejected from the generally radial passages is substantially unrestricted against free flow in any direction in the housing, and means forming a liquid-discharge passage in a wall of said housing for the output of the pump.

8. An apparatus for a closed circuit system employing a steam generator, a heat exchange apparatus supplied with steam thereby, and a condensate return line; said apparatus comprising a vented condensate reservoir tank adapted for connection to the return line, a steam turbine adapted for connection to receive steam from the generator and having an upright exhaust-steam-condensing chamber within the condensate reception space of the tank, said chamber having a continually open outlet into the tank in a position to be always sealed by condensate in the tank, a condensate pump permanently connected for operation by the turbine and having its inlet in the tank and its outlet uncommunicated with the interior of the tank and adapted for connection with the generator, a turbine steam supply valve, and operating means for

the valve arranged and connected for operation of the valve cyclically from "on" to "off" valving positions as a function of high and low quantity respectively of condensate in the tank, whereby the reception space for turbine exhaust steam in the condensing chamber is automatically enlarged as the quantity of condensate in the tank is diminished by progression of the cycle toward completion.

9. An apparatus for a steam heating system, said apparatus comprising an open or vented tank for condensate, a low pressure steam turbine, a centrifugal condensate pump connected for operation by the turbine, a snap action valve connected to supply steam to the turbine, means arranged for operation in accordance with high and low level or quantity of condensate in the tank, said means operating to open and close the valve when the level is high and low, respectively, wall means forming a steam condensing chamber in the tank, the top of the chamber being connected to the exhaust side of the turbine in a manner to receive all the exhaust steam, and the bottom of the chamber being open and continually immersed in liquid in the tank in all relative positions of the snap action valve and its operating means, means connecting the inlet of the pump to the tank outside of the condensing chamber, and conduit means connected to the outlet of the pump and leading outside of the tank and having a portion exposed in at least the upper portion of the condensing chamber for contact with exhaust steam in the chamber at predetermined condensate levels therein.

10. In and for a steam heating system, an open or vented tank for condensate, a steam turbine, a steam valve for admitting steam to the turbine, a float movably mounted in the tank and connected to the valve by snap action means for moving the valve to full "on" and full "off" positions in accordance with predetermined high and low levels of liquid in the tank, a condensate pump in the tank connected for operation by the turbine and having a condensate inlet and a condensate outlet duct, means forming a condensing chamber in the tank connected at its top end to the turbine for reception of all

- of the turbine exhaust steam, the lower end of the condensing chamber being open below the lowest level of condensate in the tank permitted by the float and snap action means in their steam-valve-closing relative position, a portion of said condensate outlet duct occupying the condensing chamber in position to provide increasing condensing contact with the turbine exhaust steam as the reception space for such steam in the chamber increases.
- 10 11. In combination, a vented storage tank for condensate of a steam heater system, a steam turbine adapted to receive a supply of steam and having a rotary output shaft extending downwardly into the tank, a condensation pump connected to the shaft and having a condensate inlet continuously immersed in liquid in the tank, wall means forming two upright chambers, one of the chambers surrounding the pump and receiving its liquid output and the other of the chambers surrounding said one of the chambers and forming a receptacle for turbine exhaust steam, said receptacle having an opening at its lower end and in position for continual immersion in liquid contained by the tank, and the wall means forming at least one of the chambers having a steam condensating wall portion which, during the operation of the turbine, is exposed at one face to exhaust steam contained in the said other chamber in a manner such that as the depth of condensate in the said other chamber decreases, said condensating wall portion has an increasing condensating surface area exposed to exhaust steam, and said wall portion being in contact with the liquid discharged by the pump at the other face.
